UNITED STATES PATENT OFFICE.

WILLIAM WHARTON, JR., AND EDWARD SAMUEL, OF PHILADELPHIA, PENNSYLVANIA, ASSIGNORS TO WILLIAM WHARTON, JR., & CO., (LIMITED,) OF SAME PLACE.

DESIGN FOR A RAILWAY-RAIL.

SPECIFICATION forming part of Design No. 17,190, dated March 15, 1887.

Application filed January 7, 1887. Serial No. 233,704. Term of patent 14 years.

To all whom it may concern:

Be it known that we, WILLIAM WHARTON, Jr., and EDWARD SAMUEL, citizens of the United States, residing in Philadelphia, Pennsylvania, have invented a new and original Design for a Railway-Rail, of which the following is a specification.

Our design for a railway-rail is fully illustrated in the accompanying drawing, the view 10 in which is a transverse section showing the outline of the rail.

The rail has a head portion, B, connected to a depending web, A, by a neck, G, and has a laterally-projecting flange, D, the tread *d* of 15 said flange being arranged in a different horizontal plane from the tread *b* of the head. The head B has a straight portion, *e*, on its under side, and is connected to the straight portion *a* of the web A by an inclined straight 20 portion, *g*, of the neck G.

We claim—

The herein-described design for a railway-rail having in transverse section the outline illustrated, comprising a head, B, having a straight portion, *e*, on its under side, web A, 25 having a straight portion, *a*, and a neck, G, having an inclined straight portion, *g*, uniting the two portions *e a*, all substantially as shown and described.

In testimony whereof we have signed our 30 names to this specification in the presence of two subscribing witnesses.

WILLIAM WHARTON, JR.
EDWD. SAMUEL.
